CLAIM

The ornamental design for a candle handle, as shown and described.

DESCRIPTION

FIG. 1 is a perspective view of a candle handle according to my design;

FIG. 2 is a left side view of the candle handle of FIG. 1;

FIG. 3 is a right side view of the candle handle of FIG. 1;

FIG. 4 is a front view of the candle handle of FIG. 1;

FIG. 5 is a back view of the candle handle of FIG. 1;

FIG. 6 is a top view of the candle handle of FIG. 1; and,

FIG. 7 is a bottom view of the candle handle of FIG. 1.

The broken lines that are included in the figures of the drawings denote aspects of the candle handle that form no part of the claimed design.
